(57) **CLAIM**

The ornamental design for an infant seat, as shown and described.

DESCRIPTION

FIG. 1 is a perspective view of an infant seat showing our new design;

FIG. 2 is a side perspective view thereof, the electronics housing, feet, and the handle/coupling housings removed for clarity;

FIG. 3 is a rear perspective view thereof;

FIG. 4 is a left side view thereof;

FIG. 5 is a right side view thereof;

FIG. 6 is a left side view thereof, showing the rear leg retracting;

FIG. 7 is a top view thereof;

FIG. 8 is a bottom view thereof;

FIG. 9 is an elevated front view thereof; and,

FIG. 10 is an elevated rear view thereof.

The broken lines showing in FIGS. 1-10 are for illustrative purposes only and form no part of the claimed design.

In FIG. 6, the broken lines disclosure of the extended rear leg is shown to designate the degree of possible adjustment.
